UNITED STATES PATENT OFFICE

2,373,229

ESTERAMIDES

Melvin De Groot, University City, and Bernhard Keiser, Webster Groves, Mo., assignors to Petrolite Corporation, Ltd., Wilmington, Del., a corporation of Delaware

No Drawing. Original application December 27, 1941, Serial No. 424,649. Divided and this application July 1, 1943, Serial No. 493,161

10 Claims. (Cl. 260—404)

This invention relates to a new chemical product or compound, our present application being a division of our pending application Serial No. 424,649, filed December 27, 1941, now Patent No. 2,344,976 issued March 28, 1944.

The main object of our invention is to provide a new compound or composition of matter, that is an efficient demulsifier for crude oil emulsions of the water-in-oil type, and also capable of use in other arts, or for other purposes, as herein-after indicated.

Another object of our invention is to provide a practicable method for making said new compound or composition of matter.

The new chemical product or compound which constitutes our present invention, consists of a sub-resinous or semi-resinous product obtained by reaction between a polybasic carboxy acid or its equivalent, such as the anhydride, and a hydroxylated esteramide of the kind hereinafter described. Said hydroxylated esteramide is of the kind in which the amido acyl radical is derived from a monocarboxy acid having not over 5 carbon atoms and the oxyacyl radical is characterized by being derived from a monocarboxy detergent-forming acid having at least 8 and not more than 32 carbon atoms.

It is well known that certain monocarboxy organic acids containing 8 carbon atoms or more, and not more than 32 carbon atoms, are characterized by the fact that they combine with alkalies to produce soap or soap-like materials. These detergent-forming acids include fatty acids, resin acids, petroleum acids, etc. For the sake of convenience, these acids will be indicated by the formula $R'COOH$. Certain derivatives of detergent-forming acids react with alkali to produce soap or soap-like materials, and are the obvious equivalent of the unchanged or unmodified detergent-forming acids; for instance, instead of fatty acids, one might employ the chlorinated fatty acids. Instead of the resin acids, one might employ the hydrogenated resin acids. Instead of naphthenic acids, one might employ brominated naphthenic acids, etc.

The fatty acids are of the type commonly referred to as higher fatty acids; and of course, this is also true in regard to derivatives of the kind indicated, insofar that such derivatives are obtained from higher fatty acids. The petroleum acids include not only naturally-occurring naphthenic acids, but also acids obtained by the oxidation of wax, paraffin, etc. Such acids may have as many as 32 carbon atoms. For instance, see U. S. Patent No. 2,242,837, dated May 20, 1941, to Shields.

Although any of the high molal monocarboxy acids can be converted into esteramides of the kind described, by conventional procedure, it is our preference to employ hydroxylated ester-

amides derived from higher fatty acids, rather than petroleum acids, rosin acids, and the like. We have found that by far the most effective demulsifying agents are obtained from unsaturated fatty acids having 18 carbon atoms. The higher fatty acids include unsaturated fatty acids, such as oleic acid, ricinoleic acid, linoleic acid, linolenic acid, etc. One may employ mixed fatty acids, as, for example, the fatty acids obtained by hydrolysis of cottonseed oil, soyabean oil, corn oil, etc. Our preferred demulsifier is obtained from unsaturated fatty acids, and more especially, unsaturated fatty acids containing a hydroxyl radical or unsaturated fatty acids which have been subjected to oxidation or oxyalkylation, such as oxyethylation.

The esteramides of the kind herein described may be obtained in any conventional manner. They are usually derived from the low molal acids themselves; but if desirable, the functional equivalents, such as the anhydrides, acyl chlorides, or other derivatives, may be employed. Suitable acids include, of course, acetic acid, propionic acid, butyric acid, valeric acid, etc. The amide of such low molal acid may be treated with an oxyalkylating agent, such as ethylene oxide, propylene oxide, butylene oxide, or the like, so as to produce a compound of the following type:

Actually, the alkylene radical might represent an equivalent divalent radical, in which the carbon atom chain is interrupted at least once by oxygen, as

Having obtained a bis(hydroxyalkyl) amide of the kind described, such compound can then be reacted in a conventional manner with a high molal acid or its equivalent, to give an esteramide, in other words, a compound of the following type:

A procedure that is frequently more readily adaptable is simply the reaction between a low molal acid, such as acetic acid, and a material of the kind exemplified by diethanolamine, di-propanolamine, or the like. For the sake of brevity, reference hereafter will be made largely to diethanolamine and acetic acid, although other suitable reactants have already been described. The method of manufacturing esteramides is so well known that no further description is required; but for convenience, the following example is given in substantially verbatim

form, as it appears in U. S. Patent No. 2,238,928, dated April 22, 1941, to Cahn and Harris:

Example A

(1) 224 grams of methyl acetate (3 moles) and 210 grams of diethanolamine (2 moles) were mixed together, two layers forming at first, the mixture becoming a homogeneous mass after a short time. The mixture was refluxed for 19 hours, at which time 90% of the diethanolamine had reacted. A portion of the reaction mixture was subjected to a vacuum of 6 millimeters at 60° C., in order to drive off the volatile material, i. e., the unreacted methyl acetate and the methyl alcohol which was formed during the reaction. The residue, upon titration, showed a content of 4.64% of free diethanolamine. To 192.5 grams of this residue, 34.7 grams of methyl acetate were added and the mixture was refluxed for 3½ hours. The resulting reaction product was then freed from its low boiling constituents, i. e., the methyl alcohol and unreacted methyl acetate, by maintaining the mass at 70° C., under a pressure of 6 millimeters. The residue contained approximately 0.8% of unreacted diethanolamine, based upon a determination of the alkalinity of said residue by titration. The product was a light yellow colored syrup, soluble in water, and contained a compound which was essentially the acetic acid amide or diethanolamine, having the following formula:

(2) 51.0 grams (½ mole) of the acetic acid amide of diethanolamine produced as described in part 1 hereof, and 38.0 grams (½ mole) of lauric acid were heated together for 15 minutes at approximately 200° C., while passing carbon dioxide gas through the reaction mixture. At the end of the 15 minutes, the free lauric acid had decreased to 1.3%. The product was a yellow colored syrup, dispersible in water and having good emulsifying and dispersing properties. It could be salted out of its solution by the addition thereto of sodium chloride. The product consisted essentially of a compound having the following formula:

Illustrating somewhat similar types of reactions, see (U. S. Patent No. 2,238,902, dated April 22, 1941, to Katzman and Harris, and also U. S. Patent No. 2,257,183, dated April 30, 1941, to Munz and Troskan).

In view of what has been said, it will be obvious that hydroxylated esteramides of the kind herein employed as reactants, may be obtained in various manners, including those described in the patents previously mentioned. As illustrating such hydroxylated esters, reference is made to the following formulas:

In the above formulas, RCO represents the acyl radical derived from an acid having 5 carbon atoms or less, such as acetic, propionic, butyric, etc. OHR'CO represents the acyl radical of a hydroxylated acid, such as ricinoleic acid, hydroxystearic acid, or similar acids obtained by oxidation, such as blown oleic acid or acids obtained by the hydrolysis of blown olein. Such acyl radicals all contain at least 8 and not more than 32 carbon atoms and are apt to contain 18 carbon atoms. R'CO is the acyl radical derived from a non-hydroxylated monocarboxy detergent-forming acid, particularly an unsaturated acid, such as oleic acid, linolenic acid, etc. It is understood, of course, that a mixture of fatty acids might be employed instead of a single fatty acid. R''' is a hydrocarbon radical having 4 to 12 carbon atoms.

In examining the above formulas, it is to be noted that comparable products might be obtainable from monobutanolamine, dibutanolamine, monopropanolamine, dipropanolamine, monoglycerylamine, diglycerylamine, or the like, instead of being derived from monoethanolamine or diethanolamine. Similarly, the products shown in the last two formulas are derived from tris(hydroxymethyl) aminomethane. Similar derivatives may be derived from 2-amino-2-ethyl-1, 3-propanediol and 2-amino-2-methyl-1, 3 propanediol.

The hydroxylated esteramides may, of course, be derived in any other suitable way, such as reaction with ammonia, followed by oxyethylation, or some other suitable process. Thus, the low molal acids themselves, or, if desirable, the functional equivalents, such as the anhydrides, acyl chlorides, or other derivatives, may be reacted with ammonia, or a primary amine, such as any suitable alkylamine, or an alicyclic amine, or an aralkylamine, to give the amide or substituted amide; in any event, a compound containing at least one amino hydrogen atom. Suitable amines include butylamine, amylamine, octylamine, decylamine, cyclohexylamine, benzylamine, phenylamine, etc. Generally speaking, when an amine is used instead of ammonia for reaction with a low molal acid, one must employ a hydroxylated detergent-forming acid, such as ricinoleic acid, in order to insure an available alcoholic hydroxyl group for subsequent reaction with the polybasic carboxy acid or its equivalent. This is readily understandable by considering the reaction in-

volving acetic acid and butylamine. The substituted amide so obtained can be treated with ethylene oxide, and then reacted with oleic acid to give a substituted esteramide. Such substituted esteramide, however, is not reactive toward phthalic anhydride by esterification reaction, in view of the absence of an alcoholic hydroxyl radical. If, however, ricinoleic acid is employed as the reactant to supply the high molal oxyacyl radical, then the hydroxyl radical which is part of the ricinoleyl radical would serve as a reactive function for combination with phthalic anhydride or the like by esterification. Lactic acid or the like might supply an alcoholic hydroxyl radical.

An alternate procedure, in case such compounds are derived from butylamine, cyclohexylamine, benzylamine, or the like, is to use glycid or the like as an oxyalkylating agent, thus introducing at least two hydroxyl radicals, one of which may be employed for esterification with oleic acid, and the other one, for esterification with phthalic acid or the like. 15 20

The simpler procedure is to prepare the amide from ammonia, and such amide of a low molal acid may be treated with an oxyalkylating agent, such as ethylene oxide, propylene oxide, butylene oxide, glycyl, or the like, to produce a compound of the following type:

Actually, the alkylene radical might represent an equivalent divalent radical in which the carbon atom chain is interrupted at least once by oxygen; i. e., the low molal amide, instead of being treated with two moles of ethylene oxide or the like, might be treated with four moles or six moles of ethylene oxide, or even more.

In any event, the reaction of the hydroxylated esteramide of the kind described with a polybasic carboxy acid or its functional equivalent, such as the anhydride, is a well known reaction and is nothing more or less than an esterification reaction of the kind employed to produce phthalated castor oil, phthalated ricinoleamide, etc. For instance, common comparable reactions are described in U. S. Patents No. 1,976,602, to De Groot, Keiser and Adams, dated October 9, 1934, and U. S. Patent No. 2,078,652, to De Groot and Keiser, dated April 27, 1937.

Briefly stated, the molar combinations of the reactions selected depend upon the available number of hydroxyl groups and may be illustrated by the following examples:

Example 1

One pound mole of the esteramide derived by reaction between equimolar portions of bis(hydroxyethyl) acetamide and ricinoleic acid, is heated with one pound mole of phthalic anhydride at approximately 145-165° C., until esterification is complete, as indicated by the substantial elimination of one alcoholic hydroxyl radical. The product so obtained has one free hydroxyl radical and one free carboxyl radical. 60 65

The following reaction will serve to exemplify the formation of the foregoing compound: OH_2RCOOH indicates ricinoleic acid.

Example 2

The product is prepared in the same manner as described in the previous example, except that the substituted acetamide is derived from oleic acid instead of ricinoleic acid.

The following reaction will serve to exemplify the formation of the foregoing compound: R:COOH indicates oleic acid.

Example 3

The same procedure is followed as in Example 1, except that two moles of phthalic anhydride are employed instead of one mole, and the final esterification product is characterized by the substantial absence of any free hydroxyl radical and by the presence of two free carboxyl radicals.

The following reaction will serve to exemplify the formation of the foregoing compound:

Example 4

Tris(hydroxymethyl) aminomethane is reacted with acetic acid to give a comparable substituted acetamide. Such acetamide is reacted with ricinoleic acid to give an esteramide. Such esteramide is substituted in Examples 1 and 3, preceding.

The following reactions will serve to exemplify the formation of the foregoing compound:

Example 5

The substituted acetamide derived from bis-(hydroxymethyl) aminomethane in the manner described in Example 4, preceding, is reacted with oleic acid to give the corresponding esteramide. Such esteramide is converted into an esterified

product in the manner described in Example 2, preceding.

The following reactions will serve to exemplify the formation of the foregoing compound:

Example 6

Acetic acid is reacted with monoethanolamine to give the corresponding hydroxylated amide. Such amide is then esterified with ricinoleic acid to give the esteramide. Such esteramide is reacted with phthalic anhydride in equimolar proportions by an esterification reaction to give the esterified final product having one free carboxyl radical.

The following reactions will serve to exemplify the formation of the foregoing compound:

Example 7

Acetic acid is converted into the substituted amide by reaction with amyloxine and then treated with two moles of ethylene oxide to give the hydroxylated amide. Such amide is then reacted with ricinoleic acid to give the esteramide. Such esteramide is then reacted with phthalic anhydride in equimolar proportions to give the final product having a free carboxyl radical.

The following reactions will serve to exemplify the formation of the foregoing compound:

Example 8

In the preceding examples, where amyloxine is used as a reactant, cyclohexylamine or benzylamine is substituted.

The products obtained may be indicated in the following manner:

Example 9

In the preceding examples, where oleic acid is employed to introduce an acyloxy radical, naphthenic acids, resin acids, or oxidized acids are substituted.

In previous formulas following under the heading of Example 2 and Example 5, if R_1 is replaced by R_2 with the understanding that $R_2\text{COOH}$ represents a naphthenic acid or a resin acid, then such formulas involving the use of such radical R_2 , properly depict the composition.

Example 10

In the preceding examples, where phthalic anhydride is used, maleic anhydride or oxalic acid is employed. In such instances where oxalic acid is employed, it is desirable to use a lower temperature, in view of the fact that oxalic acid, or most of its functional equivalents, decompose at a temperature as high as 145° to 165° C., or thereabouts, and instead a temperature of 105 to 112° C. should be employed. Such lower temperature requires longer time for esterification to take place.

As an illustration of some of the previous formulas, the divalent radical

derived from maleic anhydride, replaces the divalent aromatic radical C_6H_4 derived from phthalic anhydride.

Esterification can be conducted in the usual

manner, simply employing heat to drive off the water formed. In some instances, where an anhydride is employed, water may not be formed. If desired, one may pass a dried, inert gas, such as dried nitrogen gas, through the mass to hasten esterification. Esterification is also hastened at times by the presence of a mere trace of a suitable acid, such as benzene sulfonic acid. In other instances, the reaction is most suitably conducted in the presence of an inert high boiling solvent, such as xylene. The xylene is continuously distilled under a reflux condenser, condensed by such condenser, and returned to the reaction chamber through a trap. The xylene vapors carry off the water, which is removed after being condensed by the trap. This is a conventional procedure, commonly employed in this type or similar types of reaction.

Although we prefer to use phthalic anhydride as the most desirable source of the polybasic carboxy acid, one may use other polybasic carboxy acids or their anhydrides, such as succinic, malic, fumaric, citric, maleic, adipic, tartaric, glutaric, diphenic, naphthalic, oxalic, pimelic, suberic, azelaic, sebacic, etc. Naturally, a simple derivative of a polybasic acid, such as chlorophthalic acid, can be used as advantageously as phthalic acid itself, although there is no added advantage in the use of the more costly chemical compounds.

In view of the large number of reactants and types of materials described, it may be well to note those which we particularly prefer. It has been pointed out that we prefer to use unsaturated fatty acids as the source of the high molar acyloxy radical, and particularly the hydroxylated fatty acids commonly available, to wit, ricinoleic acid. We prefer to use phthalic acid, maleic acid, or their anhydrides, or oxalic acid as the source of the polybasic carboxy acid. We prefer to use acetic acid or its equivalent as the source of the low molar acyl radical. We prefer to use monoethanolamine or diethanolamine as the reactant for formation of the substituted amide employed for subsequent reaction to produce the esteramide.

In view of what has been said, it is apparent that the hydroxylated esteramides of the kind described previously may be considered, for the sake of simplicity, as being in the class of an alcohol, i. e., a monohydric or polyhydric alcohol. If an alcohol is indicated by the formula $Y'(OH)_n$, where n indicates the number one or more, and if a polybasic acid body be indicated by the formula $X'(COOH)_n$, where n indicates the number 2 or more, then the reaction between a monohydric alcohol and a polybasic acid will result in a compound which may be indicated by the following formula; $YX(COOH)_{n'}$, where n' indicates the number one or more, and which is in reality a contraction of a more elaborate structural formula, in which X' and Y' are joined by a carboxyl radical or residue. Assuming, however, as would be true in the majority of cases, that the alcohol actually would be a polyhydric alcohol, and that the acid body would be a polybasic in nature, for instance, if one employed a diphthalate of a polyhydroxylated esteramide of the kind previously described, then examination reveals that the formula might result in a combination, in which there were neither residual carboxyl radicals, nor residual hydroxyl radicals, or might result in compounds in which there were residual hydroxyl radicals, and no residual carboxyl radicals, or compounds where there might be residual carboxyl radicals and no residual hydroxyl radi-

cals, or there might be both. This is indicated by the following:

in which q indicates a small whole number (one in the case of a monomer, and probably not over 20 and usually less than 10), and m' and n' indicate the number 1 or more, and m'' and n'' indicate zero or a small or moderately sized whole number, such as zero, one or more, but in any event, probably a number not in excess of 10-15. Naturally, each residual hydroxyl could combine with a phthalic acid body or its equivalent, or with a similar compound derived from a tribasic acid, such as citric acid; and in such event, there would be a large number of free or uncombined carboxyl radicals present, possibly 20 or more. Actually, the preferable type of reagent would be more apt to include less than 20, and in fact, less than 10 free hydroxyl radicals. It is not necessary to remark that the residual carboxyl radicals can be permitted to remain as such, or can be neutralized in any suitable manner, such as conversion into salts, esters, amides, amino esters, or any other suitable form. Usually, such conversion into salt form would be by means of sodium hydroxide, potassium hydroxide, calcium hydroxide, magnesium hydroxide, ammonium hydroxide, amylamine, butanoiamine, ethanolamine, diethanolamine, triethanolamine, cyclohexanolamine, benzylamine, aniline, toluidine, etc. Conversion into the ester would be by means of a monohydric alcohol, such as methyl alcohol, ethyl alcohol, propyl alcohol, butyl alcohol, hexyl alcohol, octyl alcohol, decyl alcohol, ethylene glycol, diethylene glycol, glycerol, diglycerol, triethylene glycol, or the like. One could employ an amino alcohol so as to produce an ester.

We have found, however, as suggested, that the most suitable products are sub-resinous, semi-resinous, or balsam-like products, and are preferably derived from polyhydroxylated reactants, i. e., polyhydroxylated esteramides. We have found that such products are soluble to a fairly definite extent; for instance, at least 5% in some solvent such as water, alcohol, benzene, dichlor-ethyl ether, acetone, cresylic acid, or the like. This is simply another way of stating that it is preferable, if the product be one of the sub-resins, which are commonly referred to as an A resin, or B resin, as distinguished from a C resin, which is a highly infusible, insoluble resin (see Ellis, "Chemistry of Synthetic Resins," 1935, page 862, et seq.).

In recapitulating what has been said previously, the sub-resinous, semi-resinous, or balsam-like product herein contemplated may be indicated by the following formula:

in which the characters have their previous significance, and q' represents a small whole number not greater than 5, and x' represents a small whole number not greater than 5; Z represents a hydrogen ion equivalent, such as a metallic atom, organic radical, etc.

It will be noted that compounds of the type just described having at least one hydrophobe nucleus are designated as being "polar" when there is present either an unesterified hydroxyl

radical, or an unesterified carboxyl radical, or both. We have found that the polar type of material is by far the most effective for demulsification, and it is our preference to use such type. Indeed, this particular type is so much more effective for demulsification than the non-polar type, that it may be considered in essence an invention within an invention.

The presence of a low molal acyl group, particularly when derived from a non-hydroxy acid, such as acetic acid, butyric acid, and the like, has a definite functional effect that is difficult to explain. In numerous instances the presence of such radical in the selected compound, instead of an amino hydrogen atom, results in markedly greater effectiveness as a demulsifier. One possible explanation may reside in the fact that the presence of an amino hydrogen atom or the presence of two amino hydrogen atoms, ordinarily may contribute to association in the presence of hydroxylated compounds, to a greater extent than when an acyl radical of the kind described is present as a substituent for an amino hydrogen atom. Regardless of whatever the correct explanation may be, the effectiveness of the new compounds as demulsifiers in comparison with kindred compounds, is readily demonstrable.

Compounds of the kind herein contemplated may be used as plasticizers or softening agents in the manufacture of resin-like materials. They are also of distinct value as a break inducer in the doctor treatment of gasoline or the like, as described in U. S. Patent No. 2,137,223, to Sutton, dated May 9, 1939.

Having thus described our invention, what we claim as new and desire to secure by Letters Patent is:

1. A sub-resinous ester of the following formula:

in which x and y are small whole numbers not greater than 10 and m , n , and m' are small whole numbers not over 10, and including zero; Z is a cation; X is the polycarboxy acid radical of a polycarboxy acid having less than 4 carboxyl radicals and less than 15 carbon atoms, and Y is a hydroxylated esteramide radical containing in turn: (a) an amido-linked saturated low molal monocarboxy acid acyl radical having not over 5 carbon atoms; and (b) at least one monocarboxy detergent-forming acid acyloxy radical having at least 8 and not more than 32 carbon atoms, and linked by a divalent aliphatic radical to the amido nitrogen atom; and with the added pro-

viso that X be joined to Y by an ester linkage only.

2. The ester described in claim 1, wherein the low molal monocarboxy acid acyl radical contains oxygen atoms united to the carbonyl carbon atom only.

3. The ester described in claim 1, wherein the low molal monocarboxy acid acyl radical contains oxygen atoms united to the carbonyl atom only and that the polycarboxy acid be a dicarboxy acid.

4. The ester described in claim 1, wherein the low molal monocarboxy acid acyl radical contains oxygen united to the carbonyl atom only and that the polycarboxy acid be a dicarboxy acid, and that RCO be that of a higher fatty acid radical.

5. The ester described in claim 1, wherein the low molal monocarboxy acid acyl radical contains oxygen atoms united to the carbonyl atom only and that the polycarboxy acid be a dicarboxy acid, and that RCO be that of a higher unsaturated fatty acid.

6. The ester described in claim 1, wherein the low molal monocarboxy acid acyl radical contains oxygen atoms united to the carbonyl atom only and that the polycarboxy acid be a dicarboxy acid, and that RCO be that of ricinoleic acid.

7. The ester described in claim 1, wherein the low molal monocarboxy acid acyl radical contains oxygen atoms united to the carbonyl atom only and that the polycarboxy acid be phthalic acid, and that RCO be that of ricinoleic acid.

8. The ester described in claim 1, wherein the low molal monocarboxy acid acyl radical contains oxygen atoms united to the carbonyl atom only and that the polycarboxy acid be maleic acid, and that RCO be that of ricinoleic acid.

9. The ester described in claim 1, wherein the low molal monocarboxy acid acyl radical contains oxygen atoms united to the carbonyl atom only and that polycarboxy acid be oxalic acid, and that RCO be that of ricinoleic acid.

10. In a method for the manufacture of esters described in claim 1, the step of esterifying (A) a hydroxylated esteramide containing (a) an amido-linked saturated low molal monocarboxy acid acyl radical having not over 5 carbon atoms; and (b) at least one monocarboxy detergent-forming acid acyloxy radical having at least 8 and not more than 32 carbon atoms and linked by a divalent aliphatic radical to the amido nitrogen atom, with (B) a polybasic carboxy acid.

MELVIN DE GROOTE.
BERNHARD KEISER.
